W. E. VAN DORN

FRICITION DRAFT GEAR

Filed Jan. 12, 1921

INVENTOR.

W. E. van Dorn
BY
Chamberlin & Prendenrich

ATTORNEY.

UNITED STATES PATENT OFFICE.

WILLIAM E. VAN DORN, OF CHICAGO, ILLINOIS.

FRICTION DRAFT GEAR.

Application filed January 12, 1921. Serial No. 436,646.

To all whom it may concern:

Be it known that I, WILLIAM E. VAN DORN, a citizen of the United States, residing at Chicago, county of Cook, State of Illinois, have invented a certain new and useful Improvement in Friction Draft Gears, and declare the following to be a full, clear, and exact description of the same, such as will enable others skilled in the art 10 to which it pertains to make and use the same, reference being had to the accompanying drawings, which form a part of this specification.

My invention has for its object to produce 15 a simple, novel, efficient, durable and compact friction draft gear for use on railway cars and other places where shocks in opposite directions are to be cushioned.

The various features of novelty whereby 20 my invention is characterized will herein-after be pointed out with particularity in the claims; but, for a full understanding of my invention and of its object and advantages, reference may be had to the following detailed description taken in connection with the accompanying drawing, wherein:

Figure 1 is a longitudinal vertical section through a draft gear arranged in accordance with the preferred form of my invention, 30 taken approximately on line 1—1 of Fig. 2, the lower half of the rear spring seat being shown broken away;

Fig. 2 is a section taken approximately on line 2—2 of Fig. 1, parts at the rear end of 35 the gear being shown in plan;

Fig. 3 is a section taken approximately on line 3—3 of Fig. 1; and

Fig. 4 is a side elevation of one of the longitudinally-movable friction elements of 40 which there are two.

Referring to the drawing, 1 and 2 are followers adapted to engage with the usual stops on the underframe of a railway car, these followers being in the form of shallow rectangular lidless boxes; the open side of the forward follower, 1, being directed rearwardly and the open side of the other follower being directed forwardly. In the bottom of each box is a ridge, 3, extending entirely across 45 the box along one of the major axes of the latter; these ridges being vertical in the arrangement shown. Each ridge is roughly triangular or wedge-shaped in cross section, the base of the triangle or wedge being next to the bottom of the box, and the apex pointing toward the opposite follower. The

two sides of each ridge between the base and the apex are either friction surfaces or are provided with wearing shoes. In the arrangement shown, the exposed sides of each ridge are protected by loose wearing shoes, 4. In order to give to the structure a certain degree of flexibility, the surfaces of contact between the ridges and the shoes are not made flat but they are segments of cylindrical surfaces as indicated at 5. This arrangement permits the shoes to rock to a limited extent upon the ridges and thus makes it possible to obtain full contact between the various frictional surfaces to be hereinafter 70 explained. The outer face of each of the shoes is made flat and serves as one of the effective friction surfaces. Side by side behind the front follower are two spring seats, 6 and 7. Two similar spring seats, 8 and 9, are arranged just in front of the rear follower. Each of the forward spring seats has a forwardly-extending projection, 10, provided with an inclined friction face spaced apart from but parallel with the friction face on the corresponding shoe. Similarly, each of the rear spring seats has a rearwardly-extending projection, 10, provided with an inclined friction face parallel to but spaced apart from the friction face of the 85 adjacent shoe.

Between each shoe and the friction face on the adjacent spring seat is a flat friction plate, 11, narrower than either of the two friction faces between which it is placed. 90 Each of the front friction plates is connected with a corresponding friction plate at the rear so as to form therewith a single unit. This connection may conveniently be effected by making each front friction plate and the corresponding rear friction plate 95 the end members of a rectangular frame whose other two members, 12 and 13, are spaced apart far enough by the members 11 and are long enough to permit each frame 100 to embrace one of the forward spring seats and the corresponding rear spring seat while the two friction elements, 11, thereof are in operative relation to their co-operating friction surfaces. Between each pair of spring seats is placed the usual heavy draft spring, 14, there being one of these springs on each side of the longitudinal axis of the gear. The spring seats are prevented from moving laterally by any suitable means which will 110 not prevent them from adjusting themselves in the longitudinal direction as wear takes

place. In the arrangement shown, the body portions of the spring seats lie outside of the box-like followers while the wedge-shaped projections extend into the latter.

- 5 Along the free edges of the side walls of each of the boxes are inwardly-projecting flanges, 15. Each of the projections, 10, is provided with a vertical groove or seat, 16, in its outer face. In each of the grooves or seats, 16, rests a vertical roller or pin, 17, the parts being so proportioned that when they are assembled, the pins will be prevented from passing out of the open sides of the boxes by reason of their engagement with the flanges, the pins in turn preventing the withdrawal of the projections on the spring seats. However, as wear takes place, the pins or rollers permit the spring seats to move inwardly toward the boxes. Furthermore, 20 when the springs are removed from the gear, the spring seats are free to rock on the pins or rollers and be swung laterally out of operative relation to the followers.

- In assembling the parts of the draft gear, 25 all of the elements except the springs are first placed in proper relation to each other and the springs are then placed in position under an initial tension; the pressure of the springs on the spring seats holding them 30 in position and preventing them from accidentally rocking out of place. In this condition the device is a complete unit ready to be placed in the car without requiring anything further to be done with it in the 35 way of assembly or adjustment. When the device is to be placed on a car it is simply slipped into the yoke, 18, of a drawbar and brought in operative relation to the follower stops when the drawbar is mounted in position 40 on the car. No means are required to hold the springs in place, since they will not drop out during the ordinary treatment to which the assembled unit will be subjected before being placed on a car and, after the 45 unit has been placed on a car, the frame members or cheek plates of the latter will prevent the springs from coming out.

- Normally the parts are in the positions 50 illustrated in Fig. 2 of the drawing. When a pull comes upon the drawbar, the forward follower remains stationary while the rear follower moves ahead. The connecting pieces, 12 and 13, between the friction plates 11, act as struts between the two followers 55 and therefore the rear follower can approach the other only by causing the friction plates 11 to slide along the shoes between which and the friction faces on the spring seats they are frictionally held. The farther the 60 rear follower moves ahead, the greater will be the compression of the springs and therefore the greater will be the pressure between the relatively movable friction surfaces. In other words, the frictional resistance increases with the load. Under a buffing shock 65

the rear follower remains stationary and the forward follower moves back. The action of the friction devices is, however, precisely the same as that just described.

It will be seen that the parts that are subjected to wear are comparatively simple and can therefore readily be replaced. It will furthermore be seen that although there are four friction shoes, four spring seats, and two frame-like devices, all of the shoes are 70 interchangeable, all of the spring seats are interchangeable, and the two frames are interchangeable; so that only three different kinds of parts need be carried in stock for repair purposes. The followers are not required to have the properties of an efficient friction device and may therefore be made of malleable iron or cast steel which will be strong and tough and therefore capable of 75 withstanding long hard usage. It will also be seen that all of the parts of my improved device, aside from the springs, are comparatively small and light so that a high degree of compactness is secured and it is always possible to secure full spring capacity whenever 80 my improved friction gear is substituted in existing equipment for a simple spring gear.

I claim:

1. In a friction draft gear, two followers each having a central wedge-shaped ridge on the side directed toward the other follower, two spring seats arranged side by side behind the front follower, two spring seats arranged side by side in front of the rear follower, each spring seat having inclined friction faces paralleling the inclined sides on said ridges, springs arranged between corresponding front and rear spring seats, friction plates each clamped between one of said 95 friction faces and the adjacent inclined face on the corresponding ridge, and means cooperating with said spring seats to prevent them from being spread apart in the lateral direction, and means connecting each forward friction plate with the corresponding rear friction plate so as to cause them to 100 move in unison with each other.

2. In a friction draft gear, two followers each having a central wedge-shaped ridge on the side directed toward the other follower, two spring seats arranged side by side behind the front follower, two spring seats arranged side by side in front of the rear follower, each spring seat having inclined friction faces paralleling the inclined sides on said ridges, springs arranged between corresponding front and rear spring seats, frame-like members each embracing one of the forward spring seats and the corresponding rear spring seat, and means cooperating with said spring seats to prevent them from being spread apart in the lateral direction, the front and rear elements of 115 said frame-like members lying between and 120

- frictionally engaging the friction surfaces on said ridges and the friction surfaces on said spring seats.
3. In a friction draft gear, two followers each having a central wedge-shaped ridge on the side directed toward the other follower, two spring seats arranged side by side behind the front follower, two spring seats arranged side by side in front of the rear follower, each spring seat having inclined friction faces paralleling the inclined sides on said ridges, springs arranged between corresponding front and rear spring seats, friction plates each clamped between one of said friction faces and the adjacent inclined face on the corresponding ridge, means connecting each forward friction plate with the corresponding rear friction plate so as to cause them to move in unison with each other, and means engaging said spring seats to hold them against lateral displacement while permitting them to move longitudinally relatively to the corresponding followers to compensate for wear.
- 25 4. In a friction draft gear, two followers each having a central wedge-shaped ridge on the side directed toward the other follower, shoes lying loosely against the two sides of each ridge, the engaging surfaces between the shoes and the ribs being curved to permit the shoes to shift through a limited angle, two spring seats lying side by side behind the front follower, two spring seats lying side by side in front of the rear follower, each spring seat having an inclined friction face spaced apart from and parallel with one of said shoes, two springs between the front and rear spring seats, a friction plate lying between each shoe and the co-operating friction face on the adjacent spring seat, and means co-operating with said spring seats to prevent them from being spread apart in the lateral direction and means connecting each front friction plate with the corresponding rear friction plate so as to join them into a single unit.
5. In a friction draft gear, two box-like followers having their open sides directed toward each other, each box having in the bottom thereof a central wedge-shaped ridge extending across the same, two spring seats lying side by side adjacent to the open side of each of said boxes, each spring seat having a part projecting into the adjacent box and provided with an inclined friction face parallel with the adjacent side of the corresponding ridge, two frame-like members each embracing one of the front spring seats and the front and rear elements of said frame members lying between and engaging the friction surfaces on the spring seats and the adjacent sides of the said ridges, and means co-operating with said spring seats to prevent them from being spread apart in the lateral direction and springs between the front spring seats and the rear spring seats.
6. In a friction draft gear, two box-like followers having their open sides directed toward each other, each box having in the bottom thereof a central wedge-shaped ridge extending across the same, two spring seats lying side by side adjacent to the open side of each of said boxes, each spring seat having a part projecting into the adjacent box and provided with an inclined friction face parallel with the adjacent side of the corresponding ridge, two frame-like members each embracing one of the front spring seats and the front and rear elements of said frame members lying between and engaging the friction surfaces on the spring seats and the adjacent sides of the said ridges, springs between the front spring seats and the rear spring seats, and means between each said part and the adjacent side wall of the corresponding box preventing the withdrawal of said part by a direct longitudinal movement when all of the elements of the gear are assembled but permitting it to be swung out of the box when the springs are removed.
7. In a friction draft gear, two box-like followers having their open sides directed toward each other, each box having in the bottom thereof a central wedge-shaped ridge extending across the same, two spring seats lying side by side adjacent to the open side of each of said boxes, each spring seat having a part projecting into the adjacent box and provided with an inclined friction face parallel with the adjacent side of the corresponding ridge, two frame-like members each embracing one of the front spring seats and the corresponding rear spring seat, the front and rear elements of said frame members lying between and engaging the friction surfaces on the spring seats and the adjacent sides of the said ridges, springs between the front spring seats and the rear spring seats, the side walls of said boxes adjacent to said parts on the spring seats having inwardly-directed flanges, said parts having in their outer faces grooves or seats parallel with said flanges, and rollers resting in said seats and engaging with the corresponding flanged side walls.

In testimony whereof, I sign this specification.

WILLIAM E. VAN DORN.
